JUDSON O. YOUNG, OF SPRINGFIELD, MASSACHUSETTS.

CLOTHES-LINE SUPPORT.

1,145,536.

Specification of Letters Patent.

Patented July 6, 1915.

Application filed May 5, 1915. Serial No. 25,941.

To all whom it may concern:

Be it known that I, JUDSON O. YOUNG, a citizen of the United States of America, residing in the city of Springfield, county 5 of Hampden, and State of Massachusetts, have invented certain new and useful Improvements in Clothes-Line Supports, of which the following is a specification.

This invention relates to improvements in 10 clothes line supports, of the type which are adapted to be readily attached to and detached from the uprights or posts of a piazza.

In general, the invention comprises a pair 15 of parallel rods that are rigidly connected or attached to the posts or uprights of a porch and that extend directly outward from the posts and with means for slidably carrying a series of clothes line attaching devices that can be easily moved outward or inward on the rods. I am aware 20 that it is not new to support a series of parallelly arranged clothes lines on outwardly extending rods, but this clothes line support is intended to be an improvement 25 on those now in use by providing a construction that is rigid and one that can be readily attached to or detached from the supporting posts of a piazza. It is also intended 30 to have provisions for readily removing ice from the rods which carry the runners to which the lines are attached.

Referring to the drawings: Figure 1 is a top plan view of the rods that are adapted 35 to be attached to the piazza posts, the posts being indicated in section, also showing the runners on the rods to which the clothes lines are secured; Fig. 2 is a side-elevational view of one of the runners, showing means 40 for attaching the rods to the side of a post, also the device for spacing the rods or tubes from each other at their outer ends and a supporting brace that is attached to the lower rod and connected to the post; Fig. 45 3 is a detail sectional view on line 3—3 of Fig. 2, showing a drip cock to draw off the hot water that is used for melting ice or sleet that may have accumulated on the upper rod; Fig. 4 is a detail view on the line 4—4 of Fig. 2; Fig. 5 is a detail sectional view on a vertical plane passing through the axis of the parallel bars; Fig. 6 is a side elevational view of one of the runners to which the end of the clothes line is 50 attached; Fig. 7 is a sectional view on the line 7—7 of Fig. 6; and Fig. 8 is a perspec-

tive view of that portion of a runner to which the end of the line is adapted to be readily attached after it is drawn into a taut condition.

Referring to the drawings in detail, the posts of a porch are indicated in section at 1 and 2.

3 designates a plate for attaching the rods 4 and 5 to the posts. This plate, as shown 65 in detail in Fig. 5, is formed with oppositely extending ears 6 and 7 through which bolts or other securing devices are passed, as indicated at 8. This attaching plate is also formed with two cylindrical enlargements in which openings 8' and 9 are 70 formed. The openings 8' and 9 are preferably threaded in order to readily attach the bars 4 and 5 thereto. The bars 4 and 5 are preferably made from tubing in order to 75 secure the necessary lightness and strength. Their outer ends are secured together in spaced relation to each other by means of the plate 12 which is formed with two inwardly projecting lugs 13 that are secured 80 to the bars 4 and 5 by any suitable means as by a pin. The lower bar has an additional attachment to the post 1 by means of the inclined brace 14 which is for the purpose of making the device more rigid and permanent since it will take up any stress that 85 may be exerted on the outer ends of the bars, as there will be a considerable leverage that will tend to exert a twisting or rotary motion on the plate 3.

In order to attach the clothes lines, which are indicated at 15, to the upper bar 4, a series of independent runners are provided, a detailed view of one of which is shown clearly in Fig. 6. These runners comprise 95 a cylindrical barrel portion 16 having oppositely tapered inner surfaces 17. Formed integral with the barrel portion 16 is an outwardly extending member 18 which is so formed as to permit the ready attachment 100 of the end of the clothes line, as shown in Fig. 8. The line, indicated at 15, is first passed through the opening 20 and then is given a reverse turn indicated at 21, then through the recess 22 which is formed with 105 inclined sides, and, finally given a second turn and passed through the conical-shaped opening 23, which exerts a pinching or binding effect on the end of the line, thereby preventing its slipping out of the member 110 18. Extending outwardly from the barrel portion 16 is a lug or projection 24. The

purpose of this projection is to enable the operator, by means of a suitable implement having a pair of spaced prongs on the end thereof, to engage the projection 24 and the 5 part 18, whereby a clothes line attaching member may be readily moved inward and outward on the bar 4, it being understood that in using this clothes line support, the clothes are first secured to the outermost 10 line 15 and are then pushed outward to the end of the bars, then the line next to the outer line is filled and pushed outward to a position near the first line and so on until all of the lines are used.

15 In sleety or stormy weather the bars are often covered with ice or snow, preventing the members 16 from being easily moved on the rods 4, and it is, therefore, necessary to remove this ice before the clothes support 20 can be used. For the purpose of removing the ice, provision is made for filling the interior of the upper bar with warm water by means of the opening 25, the water passing through this opening and into the space 25 8' of the securing plate and then into the interior of the bar 4. After the ice is melted the water can be drawn off by means of the pet cock 26.

It is to be understood that plates and bars 30 are readily reversible, that is to say, the upper bar 4 can be placed at the bottom and the bottom bar 5 at the top. Should it be necessary to secure the plates 3 on the opposite sides of the posts 1 and 2 it is only 35 necessary to reverse the plates, that is to say the rods 4 and 5 can be interchanged, the bottom rod 5 will be at the top and the top rod 4 will be at the bottom. It is to be un-

derstood that provision to introduce warm water into the lower rod would be provided 40 in case the position of the bars was reversed.

What I claim is:

1. In a clothes line support, the combination, of two pairs of parallelly arranged members, means for attaching the same to a fixed support, means for spacing the outer ends of said members and securing the same together, a series of runners located on each of the upper one of said pairs of members for attaching the ends of the clothes lines 50 thereto.

2. In a clothes line support, the combination with two pairs of tubular bars, means for attaching said bars to a suitable support, said attaching means comprising a plate formed with cylindrical shaped bearing members to receive the ends of the bars, a plate formed with projections and adapted to enter the outer ends of the tubes for securing and spacing said tubes together, the lower one of said bars having a brace connected thereto and extending to and secured to the fixed support, and a series of runners mounted on the upper bar to which the ends of the clothes lines are attached, as described.

3. In a device of the kind described, the combination, two pairs of supporting tubular bars, means for attaching the same to a suitable support, suitable line attaching devices mounted on the upper bars, and means to introduce a liquid heating medium into the bars for removing ice from the bar, as described.

JUDSON O. YOUNG.
